FRAME FOR MULTICOMPARTMENT HAND BAGS

Frank J. Quigan, Jackson Heights, N. Y., assignor to Frank J. Quigan Company, Inc., a corporation of New York

Application November 6, 1930, Serial No. 493,746

5 Claims. (Cl. 150—29)

This invention relates to an improved frame for multi-compartment handbags, and has for its primary object and purpose to provide simple, easily operated and effective means for securely latching the several hingedly connected frame members in closed position.

More particularly, the invention essentially comprehends the provision of outer and intermediate frame members together with keeper means 10 mounted on one of the intermediate frame members and a latching element carried by each of the other frame members for releasable engagement with said keeper means.

It is a further general object of the invention 15 to provide a frame for multi-compartment handbags, and latching means for the several frame members, which may be produced in various ornamental attractive forms, and in which the several parts are so constructed and assembled 20 that such improved frames may be produced at comparatively low manufacturing cost.

With the above and other objects in view, the invention consists in the improved frame for multi-compartment handbags, and in the form 25 of construction and relative arrangement of its several parts as hereinafter more particularly described, illustrated in the accompanying drawing and subsequently incorporated in the subjoined claims.

30 In the drawing, wherein I have illustrated several simple and practical embodiments of my present invention and in which similar reference characters designate similar parts throughout the several views—

35 Figure 1 is a fragmentary side elevation of a handbag provided with my improved frame and latching means therefor;

Figure 2 is a fragmentary top plan view;

40 Figure 3 is an enlarged detail transverse section taken on the line 3—3 of Figure 2;

Figure 4 is a fragmentary perspective view showing the several frame members in separated or partially opened position;

45 Figure 5 is a fragmentary end elevation illustrating the hinge connection between the several frame members;

Figure 6 is a fragmentary perspective view, similar to Figure 4, showing a slightly modified form of the device; and

50 Figure 7 is an end elevation, similar to Figure 5, of the modified construction.

Referring in detail to the drawing, 5 and 6 respectively indicate two outer frame members. Each of these members is formed from a continuous sheet metal strip which is preferably bent

into the inverted channel shaped form illustrated in the drawing, to provide a continuous outwardly opening channel. Intermediate of its ends, at spaced points, this channel frame member is bent into the desired shape, as shown in 60 the drawing, to provide end legs connected by an intermediate top portion.

As shown in Figure 4 of the drawing, between the two outer frame members 5 and 6, an intermediate frame member 7 is arranged, 65 the latter frame member being of the usual form having its channel opening inwardly throughout the length of said frame member. These several frame members at their corresponding ends are hingedly connected with each 70 other by any approved means, as indicated at 8 for relative pivotal movement.

The upper side and top edges of the outer body walls 9 of the handbag extend over the outer sides or flanges of the two frame members 5 and 6 and are engaged in the channels thereof and are securely held or fixed therein by clinching the side flanges of the frame members upon the bag material. The channel of the intermediate frame member 7 receives the upper and side 80 edges of the flexible partition wall indicated at 10 which are secured within the channel by clinching the side flanges of said frame member upon the material. The partition wall 10, in conjunction with the outer side or body walls 9 85 of the handbag thus provides two separate compartments within the handbag.

For the purpose of releasably latching the several bag frame members in opposed face to face contact to securely close the bag compartments, I provide upon the top portion of the intermediate frame member 7 a keeper plate shown at 11 which may be of any desired ornamental form. This keeper plate at its lower edge is securely fixed in any approved manner to the 90 intermediate channel wall of the frame member 7 which closes the top of the channel, and is provided with spaced openings 12 extending there-through.

To the inner wall or flange of each of the outer frame members 5 and 6 and within the channel thereof, an upwardly projecting lug 13 is welded or otherwise securely fixed, and upon the upper end of this lug and projecting inwardly therefrom, the substantially spherical latching element 14 is riveted or otherwise permanently secured. These latching elements carried by the outer frame members 5 and 6 are respectively positioned in line with the spaced openings 12 105 110

in the keeper plate 11 but in eccentric relation thereto.

In the operation of the device, as the outer and intermediate bag frame members are brought 5 into closed face to face contact with each other, the balls or spheres 14 frictionally engage and ride over the lower edges of the respective openings 12 in the keeper plate 11. Owing to the 10 resiliency of the inner flanges of the outer frame members 5 and 6, this displacement of the latching balls from their normal relation to said frame members will be yieldingly resisted so that when the outer frame members come into contact with 15 opposite sides of the intermediate frame member 7 the inner flanges of said outer frame members will resume their normal condition and securely hold the latching elements 14 in the position illustrated in Figure 3 of the drawing wherein the reduced neck portion connecting the 20 latching element with the lug 13 is positioned in the opening 12, and said latching element adjacent the reduced neck portion is yieldably held in contact upon the lower edge of said opening. Thus, in order to release either of the outer frame 25 members so as to obtain access to either of the bag compartments, it is necessary to apply considerable force or pressure against the ball or latching element 14 in order to displace the same upwardly for passage through the opening 12.

30 In Figure 6 of the drawing I illustrate a slightly modified form of a device wherein two intermediate frame members 7 and 7' respectively are provided, in addition to the outer side frame members, to receive the partition walls 10 and 35 10' respectively, and thus provide a handbag having three separate compartments. In this instance likewise, the single keeper plate 11 projects upwardly from the top wall of the frame member 7, but as shown is provided with the 40 three spaced openings 12' therethrough. One of the outer frame members 5 is provided with the latching element 14' mounted thereon in the manner above described for engagement through one of the end openings 12' in the keeper plate.

45 The intermediate frame member 7' carries a similar latching element 15 for engagement through the central opening 12' of the keeper plate. This latching element is carried by a lug similar to the lug 13 but resiliently yieldable relative to the wall of the frame member 7'. 50

The other outer frame member 6 is provided with a latching element 14' for engagement through the other end opening 12' in the keeper plate. This latter latching element 14' is carried by the lug 13' having an angularly offset part 13a which extends inwardly from the inner wall of the frame member 6. Thus when the several frame members are moved into closed position in face to face contact this offset part 13a of the lug extends over the top of the intermediate frame member 7' so that the latching element or ball 14' will properly engage through the opening 12' of the keeper plate and be disposed in the same position longitudinally of the bag frame 65 as to other latching elements 14' and 15.

In this modified form of my invention, the frame members 5 and 6, and 6 and 7' respectively may be hingedly connected in pairs, and at 8', with the bridge plate 16 illustrated in Figure 70 7 of the drawing. It will of course be obvious that my present invention might also be applied to multi-compartment handbags having a greater number of the hingedly connected intermediate members to provide additional individual compartments.

From the foregoing description considered in connection with the accompanying drawing, the novel constructions, manner of use, and several advantages of my present invention will be clearly understood. It will be seen that I have devised 80 a frame for multi-compartment handbags and the latching means therefor in which the several bag frame members may be securely latched and held in closed position by means of a single keeper plate mounted on one of said frame members. Thus the number of projecting parts is reduced 85 to a minimum and bag frames of this type may therefore be manufactured in various attractive and ornamental forms at comparatively small cost. While in the drawing, I have indicated a preferable form of the latching member 14, it will be understood that in this respect, and also as to the size, shape and form of the keeper plate, various modifications are possible.

Accordingly, in practice I reserve the privilege 90 of resorting to all such legitimate changes in the essential features of my present invention as herein disclosed, as may be fairly incorporated within the spirit and scope of the appended claims.

I claim:

1. A frame for multi-compartment handbags comprising outer and intermediate frame members, said outer frame members each having a continuous outwardly opening channel to receive the edges of one of the outer side walls of the handbag and an intermediate frame member having a continuous inwardly opening channel to receive the edge of a partition wall of the handbag, a latch means for said frame members including a keeper plate fixed to the top of the intermediate frame member and projecting upwardly therefrom, said plate having spaced openings therethrough, and an inwardly projecting latching element mounted upon the inner 110 channel wall of each of the outer frame members in eccentric relation to one of the openings in the keeper plate, whereby when said frame members are brought into face to face contact with each other, each latching element frictionally rides over the edge of one of said openings in the keeper plate and is resiliently urged to latching position in respect to said plate by the wall of the outer frame member.

2. A frame for multi-compartment handbags 125 comprising two outer frame members and a plurality of intermediate frame members and means hingedly connecting the several frame members to each other at their corresponding ends, said outer frame members each having a continuous 130 upwardly and outwardly opening channel to receive the edges of one of the outer side walls of the handbag, and said intermediate frame members each having a continuous inwardly opening channel to receive the edges of a partition wall 135 separating the interior of the bag into separate compartments, means for latching the several frame members in closed position including a keeper plate projecting upwardly from one of the intermediate frame members and provided 140 with a plurality of spaced openings therethrough, upwardly projecting lugs fixed to the inner channel walls of the outer frame members, one of said lugs having an inwardly extending offset part to project over the top of the adjacent intermediate frame member, a lug projecting upwardly from said intermediate frame member, latching elements fixed to the upper ends of the respective lugs and in eccentric relation to the respective openings in the keeper plate, 150

whereby when the outer and intermediate frame members are brought to closed position in face to face contact said latching elements are yieldably and frictionally engaged with the lower 5 edges of the respective openings in the keeper plate to releasably retain the several frame members in closed position.

3. A hand bag providing an outwardly open frame member and an inwardly open frame 10 member hinged to come into flatwise juxtaposed engagement with each other.

4. A hand bag providing a pair of outwardly open frame members, and an intermediate inwardly open frame member related with respect 15 to the first said frame members to be engaged flatwise thereby in juxtaposition thereto when the frame members are in closed position.

5. In a hand bag, a pair of main frame members of channel material opening outwardly, pouch material engaged within the channel material, said channels being pinched at their open edges, and an intermediate frame member adapted to lie between the main frame members in juxtaposition thereto when the bag is closed said intermediate member being channel shaped with its open edge directly inwardly and pinched together to compensate for the pinching of the main frame members thereby enabling the main frame members to engage the intermediate frame member flatwise on opposite sides thereof.
